(57) **CLAIM**

The ornamental design for a septic tank screen, as shown and described.

DESCRIPTION

FIG. 1 depicts a front perspective view of the septic tank screen of the present design application where a septic tank opening is depicted in broken lines to show context and forms no part of the design to be patented;

FIG. 2 depicts a top plan view of the ornamental design shown in FIG. 1;

FIG. 3 depicts a bottom plan view of the ornamental design shown in FIG. 1;

FIG. 4 depicts a side elevation view of the ornamental design shown in FIG. 1, wherein the septic tank screen has left and right symmetry; and,

FIG. 5 depicts a front elevation view of the ornamental design shown in FIG. 1, wherein the septic tank screen has front and rear symmetry.
